The ornamental design for a portable oncologic external dosimeter reader, as shown and described.

DESCRIPTION

FIG. 1 is a front perspective view of a portable oncologic external dosimeter reader illustrating our new design;

FIG. 2 is a front view thereof;

FIG. 3 is side view thereof;

FIG. 4 is an opposing side view thereof;

FIG. 5 is a rear view thereof;

FIG. 6 is a top view thereof;

FIG. 7 is a bottom view thereof;

FIG. 8 is a front view of the portable oncologic external dosimeter shown in use; and,

FIG. 9 is another perspective view of the portable oncologic external dosimeter shown in use.

The broken lines shown herein are for illustrative purposes only and form no part of the claimed design.
